UNITED STATES PATENT OFFICE.

GEORGE D. FLANDERS, OF ELLSWORTH, KANSAS.

VENEER BLOCK.

1,276,894.

Specification of Letters Patent. Patented Aug. 27, 1918.

Application filed August 13, 1917. Serial No. 185,970.

To all whom it may concern:

Be it known that I, GEORGE D. FLANDERS, a citizen of the United States, residing at Ellsworth, in the county of Ellsworth and 5 State of Kansas, have invented a new and useful Veneer Block, of which the following is a specification.

The present invention relates to a veneer block applicable to the sheathing or frame- 10 work of a building to provide the exterior finish.

It is the object of the invention to provide a veneer block which can be inexpensively manufactured and applied, to constitute an 15 inexpensive yet thoroughly efficient and attractive exterior finish for buildings.

A further object of the invention is to provide the block with novel means for attaching it to the sheathing or frame to se- 20 curely hold the block in place, and to enable the block to be moved without disturbing the adjacent blocks.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed can be made within the scope of what is claimed, without departing from the spirit of the invention.

The invention is illustrated in the accom- 35 panying drawings, wherein:

Figure 1 is an elevation of the blocks laid together.

Fig. 2 is an enlarged sectional detail on the line 2—2 of Fig. 1.

Fig. 3 is an enlarged fragmental elevation 40 of one block.

Fig. 4 is a perspective view of one of the anchor members.

Fig. 5 is a sectional detail of a block with a modified form of anchor member.

Fig. 6 is a perspective view of the modified form of anchor member.

Fig. 7 is a perspective view of a different form of block with the wire anchor mem- 45 bers.

The block 1 as illustrated is of rectangu- 50 lar contour, although it may be of any suit- able size and shape, being of slab or plate form and composed of concrete or other plastic material. The blocks can be laid in courses against the sheathing or frame, and 55 the exterior surfaces of the blocks can be of

any suitable finish. If desired, the block can be provided with a marginal groove 2 in its edges, to match the grooves of the companion blocks, for receiving mortar or 60 other bonding material, but these grooves need not be used.

The block is also provided with a marginal rabbet 3 at its outer face and along its edges, whereby the complementary rabbets 65 of the adjacent blocks provide grooves separating the faces of the blocks, to provide an ornate finish.

Each block is provided with several anchor members 5 adjacent to the edges 70 thereof, and so arranged as not to mar the face of the block.

Each anchor member 5, as shown in Figs. 2, 3 and 4, is bent from wire doubled longitudinally and having a loop 6 at its intermediate portion or bend flush with the rear surface of the block and extending to the corresponding edge thereof, said edge of the block being provided with a transverse groove 4 extending from the rabbet 3 and 80 intersecting the groove 2. The loop 6 is arranged at the rear or inner end of the groove 4. The member 5 has a portion 7 extending forwardly from the loop 6 and embedded within the block near the groove 4, and the 85 member has a portion 8 extending at an angle from the portion 7 into the block away from the edge or margin thereof, the portion 8 terminating in diverging or hook-shaped terminals 9 which constitute means for anchoring the member securely within the body of the block. These anchor members 5 are molded within the block, and are therefore embedded firmly therein, the portion 8 and terminals 9 being disposed be-

tween the front and rear faces of the block, and the portion 7 extending rearwardly to the rear surface and having the loop 6 ex- 90 tending at an angle therefrom to the rear end of the groove 4. Thus, when the block 95 is placed against the sheathing or frame 11, a nail 10 or other securing element can be readily inserted rearwardly through the groove 4 and loop 6, to be driven into the sheathing or frame, whereby the head of the 100 securing element or nail 10 will bear against the loop 6, and firmly clamp it against the sheathing or frame. In this manner, the block can be readily fastened to the supporting structure, with the securing elements at 105 the margin of the block so as not to encumber or mar the exposed face thereof, which 110

may have any suitable finish. The edges of the adjacent blocks can fit snugly together, without interfering with the attachment of the blocks to the supporting structure, and should a block become broken or otherwise injured, it can be readily removed without disturbing the others. This enables repairs to be made easily.

In the modifications shown in Figs. 5 and 10 6, the anchor member 5' is formed from a strip of metal, and this anchor member 5' embodies the outstanding apertured portion or ear 6' resembling the looped or apertured portion 6. The member 5' has a portion 7' extending forwardly from the ear 6', and a portion 8' extending at an angle from the portion 7' and provided at its end with a coiled or bent back portion 9' to properly anchor the member within the 20 block.

Fig. 7 illustrates an elongated rectangular block 1' having the marginal groove 2 and in its outer face, the transverse grooves 3' dividing the exterior surface of the block 25 into squares. This block has the wire anchor members 5 embedded therein, although the sheet metal anchor members 5' can be used.

Copies of this patent may be obtained for five cents each, by addressing the "Commissioner of Patents, Washington, D. C."

Having thus described the invention, what is claimed as new is:—

A block of the class described, provided in one edge with a transverse groove; and an anchor comprising an outer end having an aperture alined with the groove, a body disposed at right angles to said end, and a shank disposed at right angles to the body and projecting therefrom in an opposite direction to said end, said outer end of the anchor being partially embedded in the block and extending along the rear of the 40 block within the perimeter of the block and beyond the base of the groove, the outer surface of said end being flush throughout its length with the rear face of the block, the body being disposed parallel to said edge of 45 the block and being embedded in the block in spaced relation to said edge of the block, the shank being embedded in the block.

In testimony that I claim the foregoing as my own, I have hereto affixed my signature in the presence of two witnesses.

GEORGE D. FLANDERS.
